UNITED STATES PATENT OFFICE.

ARTHUR G. BOULEY, OF BOSTON, MASSACHUSETTS.

TOOL.

1,297,072.

Specification of Letters Patent. Patented Mar. 11, 1919.

Application filed May 20, 1918. Serial No. 235,647.

To all whom it may concern:

Be it known that I, ARTHUR G. BOULEY, a citizen of the United States, residing at Boston, in the county of Suffolk and State 5 of Massachusetts, have invented new and useful Improvements in Tools, of which the following is a specification.

This invention relates to tools for cutting the armor or insulation of cables and 10 particularly electric cables or wires preparatory to removing or stripping such insulation, armor or covering.

The object of the invention is to produce a cutting tool of the class referred to which 15 may be held in the workman's hand and drawn along the cable with a firm pressure, the construction of the tool being such as to prevent injury to the workman, it being practically impossible for the tool to slip 20 off the cable during the cutting operation.

With the ordinary tools for the purpose referred to now in use, workmen are frequently injured by the tool slipping from the cable and cutting the hands, and in some 25 cases, the hands come in contact with the fine steel wire fabric surrounding the core of the cable with the result that infection rapidly sets in and often times serious results follow.

30 A further object of the invention is to provide a tool of the character referred to in which provision is made for adjusting the cutting bit or blade so that any desired depth may be obtained, and a cut may be made either longitudinally of the cable 35 covering or transversely around the same.

With the above and other objects in view, the invention consists in the construction, combination and arrangement of parts, as 40 herein described, illustrated and claimed.

In the accompanying drawings:

Figure 1 is a view partly in side elevation and partly in longitudinal section of the improved tool, showing the cutting relation thereof to a cable covering.

Fig. 2 is a view taken at a right angle to Fig. 1.

Fig. 3 is a cross section on the line 3—3 of Fig. 1.

50 Fig. 4 is a cross section on the line 4—4 of Fig. 1.

Fig. 5 is a side elevation of the bit or blade holder.

Fig. 6 is a plan view of the bit or blade.

55 Fig. 7 is a sectional view taken at a right angle to Fig. 5.

Fig. 8 is a view illustrating the manner of forming a transverse cut in the cable covering.

The tool comprises an outer tubular shell 60 or casing 1 which forms also the handle of the tool, one hand of the workman being placed around the shell or casing 1, leaving the other hand free to hold the cable.

At the inner end of the tool or that end 65 which rests against the cable covering, the shell or casing 1 is formed with diverging guide fingers 2 leaving a V-shaped space between them in which the cable is positioned in the cutting operation as shown in Figs. 70 2 and 8. Mounted adjustably in the casing 1 is a bit or blade holder 3 of cylindrical formation, the body of said holder being longitudinally split at 4 from the lower end thereof upwardly a suitable distance, 75 thereby providing bit clamping portions or jaws 5 between which a bit or blade 6 is placed and held. The bit or blade 6 has an upwardly extending shank 7 which is shown as formed separately from the body of the 80 blade and secured thereto by means of a pin or equivalent fastening device 8, the lower end of the shank 7 being formed with a slot 9 to receive the adjacent end portion of the bit 6 as shown in Fig. 1.

85 The bit holder is formed with a reduced and threaded portion 10 having a smooth central longitudinal bore 11 through which the shank 7 is slidably adjustable. The end portion of the shank 11 is screw threaded as shown 90 at 12 and threaded thereon is a bit adjusting nut 13 which bears against the adjacent extremity of the reduced and threaded portion 10 of the bit holder as shown in Fig. 7. Adjacent to its end, the portion 10 of the bit holder is formed with an annular 95 groove 14 to receive the set screws 15 which are carried by the nut 13 and extend radially through threaded openings in said nut, the inner ends of the screws 15 fitting in the 100 groove 14 as shown in Fig. 7, and preventing the nut 13 from moving longitudinally upon the portion 10 of the bit holder, while permitting said nut 13 to be turned, when the screws 15 are loosened. By turning the nut 105 13, the shank 7 is moved longitudinally and a corresponding movement is imparted to the cutting bit 6 so as to provide more or less projection of the lower cutting covers of said bit. When the desired adjustment 110 of the cutting bit has been obtained, it is fixed by means of a jam nut 16, threaded

upon the portion 14 of the cutting bit and adapted to bear firmly against the adjusting nut 13 in the manner illustrated in Fig. 7.

The lower extremity of the body of the cutting bit holder is beveled or conical as shown at 17, thereby forming a depth gage as illustrated in Figs. 2 and 8 by contact with the outer surface of the insulation 18 of the cable 19. The cutting blade or bit 6 is sharpened along its side or longitudinal edges as shown at 20, the cutting operation being performed by the corners 21, the end faces 22 of the bit being flat or not edged as they do not perform any cutting operation. All four of the corners of the cutting bit 6 may be used, it not being necessary to resharpen the bit until all of said corners have been used.

The bit holder 3 is further provided with a pair of longitudinally extending grooves 23 arranged ninety degrees from each other. A set screw 24 is threaded through the shell or casing 1, the inner end of said screw being adapted for insertion in either one of the grooves 23. The set screw 24 thus prevents any relative rotative movement between the bit holder 3 and the shell or casing 1 during the cutting operation. At the same time the grooves 23 admit of the longitudinal adjustment of the bit holder 3 to obtain a desired depth of cut.

From the foregoing description, taken in connection with the accompanying drawings, it will now be understood that a cut of any desired depth may be safely made through the insulation or covering of a cable or the like, either in a longitudinal or transverse direction, and this may be accomplished without any liability of injury to the workman who may therefore perform his work rapidly and economically. The blade or bit has four cutting points or corners all of which may be used before it becomes necessary to resharpen the same. The tool is also adapted for use in connection with cables of widely varying diameters, due to the disposition of the centering or guiding fingers or projections 2.

I claim:—

1. A tool for cutting through the covering of a cable or the like, comprising a tubular casing, cable centering projections diverging from one end of the casing, a cutting bit holder mounted for movement longitudinally and partial rotation within said casing, means for adjusting said bit holder in the direction of its length to obtain greater or less projection thereof into the angle between said cable centering pro-

jections, means for maintaining said adjustment, and means for holding said holder against rotative movement.

2. A tool for cutting through the covering of a cable or the like, comprising a tubular casing, cable centering projections diverging from one end of the casing, a cutting bit holder mounted for longitudinal movement in said casing and comprising a threaded portion, a rotatable but otherwise non-shiftable threaded member engaging said threaded portion for affecting a longitudinal adjustment of said bit holder in the casing, and a cutting bit extending longitudinally of said holder and adjustable therewith and also independently thereof in the direction of its length to provide for varying the depth of cut.

3. A tool for cutting through the covering of a cable or the like, comprising a tubular casing, cable centering projections diverging from one end of the casing, a cutting bit adjustable longitudinally within said casing and projecting into the angle between said centering projections, means for adjusting said cutting bit longitudinally to vary the depth of cut thereof, said bit holder being partially rotatable in the casing, and means for limiting such rotative movement of the bit holder.

4. A tool for cutting through the covering of a cable or the like, comprising a tubular casing, cable centering projections diverging from one end of the casing, a cutting bit adjustable longitudinally within said casing and projecting into the angle between said centering projections, means for adjusting said cutting bit longitudinally to vary the depth of cut thereof, said bit holder being partially rotatable, means for limiting such rotative movement of the bit holder, and means for holding said cutting bit against rotative movement.

5. A tool for cutting through the covering of a cable or the like, comprising a tubular casing, cable centering projections diverging from one end of the casing, a cutting bit adjustable longitudinally within said casing and projecting into the angle between said centering projections, screw-threaded means for adjusting said cutting bit longitudinally to vary the depth of cut thereof, said bit holder comprising bit clamping portions between which a cutting bit is adapted to be clamped, and fastening means for said clamping portions.

In testimony whereof I affix my signature.

ARTHUR G. BOULEY.
